COMBINED BOTTLE AND CLOSURE CAP
THEREFOR

Myles Basil Hailes, Walton-on-Thames, England, assignor to Lever Brothers Company, New York, N.Y.

Filed Feb. 17, 1970, Ser. No. 21,476

Claims priority, application Great Britain Aug. 22, 1969

Term of patent 14 years

Int. Cl. D9—01

U.S. Cl. D9—117

Fig. 1.

Fig. 2.

Fig. 3.

Fig. 4.

FIG. 1 is an elevational view of a combined bottle and closure cap therefor showing my new design, the opposite side being the same in appearance as the side shown;

FIG. 2 is an elevational view looking from the right of FIG. 1, the opposite side being the same in appearance as the side shown;

FIG. 3 is a top plan view; and

FIG. 4 is a bottom plan view thereof.

I claim:

The ornamental design for a combined bottle and closure cap therefor, substantially as shown and described.
